CAN OPENER

Ferdinand E. Fender, Evanston, Ill., assignor to
Vaughan Novelty Mfg. Co. Inc., Chicago, Ill., a
corporation of Illinois

Application July 15, 1939, Serial No. 284,682

1 Claim. (Cl. 30—22)

This invention relates to an improvement in a can opener and more particularly to improvements designed to facilitate the operation thereof and to increase the safety with which the can opener may be used.

Users of can openers of the bayonet type have encountered danger in the use thereof due to the fact that the resistance of the can top to the bayonet blade tends to force the blade out of the can and if sufficient pressure is applied to the can opener handle to overcome the tendency of the blade to be forced from the can, the blade tends to complete the cut and due to the pressure to leap from the can and toward the hand with which the operator is holding the can. It is the purpose of my invention to provide a projection upon the can opener blade that will retain the blade within the can and prevent the blade point from escaping from the can during the operation and also to provide an improved fulcrum member which will prevent the blade from being forced rearward out of the can during the cutting operation.

A further object of my invention is to provide these improvements in a can opener which can be readily and cheaply constructed.

A further object of my invention is to provide an improved can opener of the familiar bayonet type with an integral lug upon the blade which, in addition to serving to retain the blade within the can during the cutting operation, also serves to space the cutting edge of the blade from the bead of the can in order to prevent the blade from biting into the can bead.

A further object of my invention is to provide the can opener with an improved fulcrum which will readily bite into the can bead and prevent any backward motion of the can opener during the cutting operation.

Further objects, advantages and capabilities of my invention will appear from the following description of a preferred embodiment thereof, taken in conjunction with the accompanying drawing, in which:

Figure 1 is a perspective view of the entire can opener showing the safety lug stamped from the blade and showing the improved fulcrum member;

Fig. 2 is a plan view of the can opener with only a fragment of the handle shown;

Fig. 3 is a detail sectional view of the fulcrum member taken on the line 3—3 of Fig. 2;

Fig. 4 is a fragmentary section of the can opener blade;

Fig. 5 is a fragmentary view of the can opener

with the blade in operating position within the can, which is shown in a fragmentary section;

Fig. 6 is an enlarged fragmentary view of the can opener blade applied to a can, which is partially shown; and

Fig. 7 is a detail perspective view of a portion of the can opener blade with an alternative form of safety lug.

Referring to the drawing, the can opener handle 11 is shown as formed of a metal strap bent to form a substantially elongated loop to be grasped by the hand and terminating at the forward end in two adjacent plates 12 and 13, between which the can opener blade 17 is securely fixed by the rivets 14. One end of the strap may be continued beyond the plate 13 to form the guide member 15 which lies parallel to the can opener blade but spaced therefrom to guide the can opener blade along the wall of the can. Pivoted within the handle loop is a corkscrew 16, which forms no part of my invention. Although the handle is shown as a formed metal strap, it can be made of other suitable materials and in other forms without departing from my invention.

The can opener blade 17 is stamped from a flat strip of metal. One end of the blade 17 is formed into the shank 18 which lies between the flat plates 12 and 13 and is securely fastened to the handle 11 by means of the rivets 14. The other end of the blade is bowed, as best shown in Figs. 3, 4 and 5, and terminates in the point 19. The upper edge 20 of the blade 17 is sharpened to improve its cutting action.

The blade, as shown, has formed integrally with it the bottle cap remover 22, which forms no part of my invention.

Integral with the blade 17 and intermediate its upper edge 20 and its lower edge 21 and located a short distance from the blade point 19 is a lug 23. In the first six figures of my drawing this lug is shown as stamped from the blade 17. This lug may also be suitably formed by welding or otherwise securing a lug upon the side of the blade, such as the alternative form shown in Fig. 7. It is essential to my invention, however, that the lug be tapered toward the blade point and that its edge nearest the upper edge 20 of the blade 17 projects abruptly from the blade face to form a distinct abutment 24.

It is also essential that the lug be mounted upon the blade face at some distance to the rear of the blade point so that the blade will have penetrated the can top to some depth and made

55

a substantial cut before the lug is forced into the can. This formation will facilitate the penetration of the can top when the blade is inserted therein and will also provide a positive stop to prevent the blade from being lifted out of the can during the cutting operation.

Intermediate the lower edge 21 of the blade 17 an ear 25 is stamped from the blade at right angles thereto. At the forward edge of this ear 25, which forms the contact edge of the fulcrum, is cut a small V-shaped notch 26, which lies between the guide member 15 and the blade 17 as shown in Fig. 2. This notch 26 provides a fulcrum upon which the can opener is operated in cutting the top from a can.

The operation of the can opener of my invention is as follows:

The can opener blade 17 is placed over the can to be opened with the can opener in substantially vertical position and with the guide member 15 outside the can and the point 19 against the top of the can adjacent the perimetral bead, by which the can top is joined to the can walls.

A portion of this bead 27 is shown in the fragmentary section of the can 28 in Figs. 5 and 6. The can top is indicated by the numeral 29 and the side wall by the numeral 30.

The can blade is forced through the can top by pressure applied to the handle 11. Sufficient length of the blade 17 must be forced into the can so that the lug 23 is below the top of the can. Thereupon the can opener may be tilted into the position shown in Fig. 6. When the can opener is tilted into that position the upper edge 20 of the blade 17 bears against the lower surface of the top of the can and the ear 25 with the fulcrum notch 26 cut into its contact edge engages the upper edge of the bead 27, as shown in Figs. 5 and 6. The fulcrum notch 26 bites into the bead 27 of the can 28 as soon as downward pressure is applied to the handle 11 and thereupon the upper edge 20 of the blade 17 shears the top 29 of the can.

Both in puncturing the can and in the cutting operation just described the lug 23 bears against the side wall of the can and spaces the blade 17 therefrom. When the can opener is operated by application of downward pressure to the handle 11, the upper edge 24 of the lug 23 encounters the fragment of the can top remaining between the blade 17 and the can bead 27, as shown in Fig. 5, and prevents further upward movement of the blade 17. The lug thus forms a positive stop to prevent the emergence of the blade from the can and also indicates to the operator that the cut has been completed and that the can opener must be advanced along the can bead for another cutting stroke. Thereupon the operator lifts the can opener into vertical position, leaving the can opener blade within the can, and moves the entire can opener forward along the can bead. The can opener is then again tilted

into the inclined position shown in Fig. 6, and the cutting operation repeated.

When the lug 23 encounters the lower surface of the can top 29, or whenever unusual resistance is encountered in the cutting operation, the force applied to the handle 11 of the can opener tends to force the can opener backward and tends to permit the blade to escape from the can. The special form of fulcrum which I have devised prevents any backward movement of the can opener in this manner. The inclined edges of the V-shaped fulcrum notch 26 cut in the flange 25 cut into the bead 27 when pressure is applied to the can opener handle, as shown in Figs. 5 and 6. This insures that upon the application of downward pressure to the handle 11 the can opener will not slide backward along the bead, but will remain in its position relative to the bead and limit the movement of the can opener to a pivotal movement upon the fulcrum.

From the foregoing, it will appear that the blade 17 in effect has two portions, the puncturing or piercing portion, which extends from the pointed end approximately to the position of the lug 23, and the shearing portion, constituting the remainder of the blade utilized to shear the can top during the successive rocking movement thereof in the operation of cutting the top from the can.

Having thus described my invention, what I claim as new and desire to secure by Letters Patent is:

A can opener of the bayonet type having a handle, and a blade secured to said handle and having a continuous cutting edge terminating in a point, a portion of the blade adjacent the point serving only as a means to pierce a can top upon initially forcing the blade into the can top, the remaining portion of the blade serving primarily as a means to shear the can top upon subsequent successive rocking movement of the blade relative to the can, a member rigid with said blade and forming a pivot for such rocking movement, said blade having an opening therein, the metal from said opening being bent sidewardly to form a lug projecting from the side of the blade in the direction of said pivot member and sloping toward the point of the blade, said opening and lug being located near the junction of the shearing portion and the piercing portion of the blade and spaced from the longitudinal edges of the blade, whereby said piercing portion may readily be forced into the can top without being obstructed materially by said lug, and said lug will serve as a limit stop by engagement with the unsevered portion of the can top to prevent the piercing portion of the blade from being accidentally withdrawn from the can top during the rocking movement of the blade incidental to use of the shearing portion of the blade.

FERDINAND E. FENDER.
